UNITED STATES PATENT OFFICE

HAL TAYLOR, OF MONCURE, NORTH CAROLINA, ASSIGNOR OF TWO-THIRDS TO JAMES F. ALASTON, OF PITTSBORO, NORTH CAROLINA

COTTON CHOPPER

Application filed May 18, 1929. Serial No. 364,071.

The present invention relates to a machine useful in growing cotton and has for its prime object to provide in the machine means for harrowing, chopping and cultivating the cotton simultaneously and said various means being controllable so as to be inoperative when desired.

Another very important object of the invention resides in the provision of a cotton chopper operable from one of the wheels of the machine.

A still further very important object of the invention resides in the provision of a machine of this nature which is comparatively simple in its construction, inexpensive to manufacture, strong and durable, easy to manipulate and adjust, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinlater more fully described and claimed.

In the drawings:

Figure 1 is a side elevation of the machine embodying the features of my invention,

Figure 2 is a top plan view thereof,

Figure 3 is a rear elevation thereof,

Figure 4 is a vertical transverse section therethrough taken substantially on the line 4-4 of Figure 1,

Figure 5 is a perspective view of the adjustable frame member for the chopping element,

Figure 6 is a vertical detailed section taken substantially on the line 6-6 of Figure 2,

Figure 7 is a perspective view of the harrow,

Figure 8 is a perspective view of one of the choppers, and

Figure 9 is a perspective view of the other chopper.

Referring to the drawings in detail it will be seen that numeral 5 denotes an elongated frame bar pivotally engaged as at 6 on the center of a front axle structure 7 hav-

ing wheels 8 journaled thereon with suitable draft means 9 associated therewith.

A triangular harrow frame 10 has harrow teeth 11 depending therefrom. An inverted U-shaped frame 12 rises from the other frame 10 and the legs of the frame 12 straddle the bar 5 and a bell crank lever 14 has one end secured to the bight or upper portion of the frame 12 and an intermediate portion journaled in the bracket structure 15 rising from the frame bar 5, so that by rocking the other end of the lever 14 the harrow may be raised and lowered in respect to the ground.

A hook 16 is pivotally mounted on the bracket structure 15 so that it may be engaged over the lever for holding the harrow in a raised position when desired.

A bracket arm 17 extends laterally and inclines downwardly from the frame bar 5 to the rear of the harrow and has journaled therein a crank shaft 18, one end of which is journaled in rear axle structure 19 having wheels 20 journaled thereon and supporting the rear end of the frame bar 5. Chopper shanks 21 and 22 have ends journaled on the crank of the crank shaft 18 and the other ends thereof are provided with chopping blades 23, 24 respectively. Intermediate portions of these shanks 21 and 22 rest in open top portions 26 of a loop frame 27 slidable through the frame bar 5 and the upper cross member 28 of the frame 27 moves in a guide structure 29 on which is pivoted a lever 30 having one end engaged on the upper cross portion 28 so that by rocking the lever 30, the choppers 21 and 22 may be swung upwardly or allowed to move downwardly as may be desired.

A pinion 31 is rotatably mounted on the crank shaft 18 and a clutch member 32 is associated between the shaft 18 and the pinion 31 and operable by a fork 33 controllable by a lever 34 pivoted on a bracket 35 extending forwardly from the rear axle structure 19.

A gear 36 is fixed to one rear wheel 29 and in mesh with the pinion 31 so that when the clutch 32 is in and moves forwardly, said crank shaft 18 is rotated by said rear wheel thereby swinging the cranks of the crank

shaft and reciprocating and oscillating the choppers as will be quite apparent.

A pair of cultivators 40 are disposed to the rear of the machine having their forward ends attached to the axle structure 19 by means of chains 41. Bars 42 rise from the cultivators and are pivotally engaged with levers 43 which extend through an opening 44 in a guide 45 one to each side of a spear head structure 46 so that these levers may be rocked downwardly and caught under the spear head to hold the cultivators raised when desired.

From the above detailed description it will be seen that I have devised a machine which permits simultaneous harrowing of the ground, stacking of the cotton, and cultivating of the ground in the order mentioned and permits any of these three mechanisms to be thrown out of operation if desired.

An attendant may be disposed on the rear axle structure within easy access of all the control levers.

It is thought that the construction, operation and utility and advantages of this invention will now be quite apparent to those skilled in this art without a more detailed description thereof.

The present embodiment of the invention has been described in detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

A machine of the class described comprising a wheeled structure, a crank shaft mounted for rotation in the structure, means for operatively connecting the crank shaft with one wheel of the structure for actuation thereby, a pair of shanks engaged on the cranks of the crank shaft, blades on said shanks, a loop frame slidable vertically through the structure and having open top pocket portions at the bottom thereof to slidably receive the shanks and support the intermediate portions thereof, a guide member for the upper portion of said frame, a lever swingably and pivotally mounted on said guide member and engaged with said frame so that by swinging the lever said frame may be raised or lowered for adjusting said shanks and blade.

In testimony whereof I affix my signature.
HAL TAYLOR.
